UNITED STATES PATENT OFFICE.

ALVA L. BROWN, OF MCKINLEY, OREGON.

MILK-CAN CLOSURE.

1,192,745.

Specification of Letters Patent. Patented July 25, 1916.

Application filed February 2, 1916. Serial No. 75,761.

To all whom it may concern:

Be it known that I, ALVA L. BROWN, a citizen of the United States, residing at McKinley, in the county of Coos, State of Oregon, have invented certain new and useful Improvements in Milk-Can Closures; and I do hereby declare the following to be a full, clear, and exact description of the invention, such as will enable others skilled in the art to which it appertains to make and use the same.

The present invention is directed to improvements in milk can closures, and has for its object to so construct a device of this character that when in place the danger of the closure becoming accidentally disengaged is eliminated.

A further object of the invention is to provide a closure of this type so constructed that should the can be tampered with in an attempt to open the same during transportation the card bearing the consignee's name will be mutilated.

A further object of the invention is to provide a device of this character so constructed that when the closure is in place the can will be firmly sealed and practically air tight.

With these and other objects in view, this invention resides in the novel features of construction, formation, combination and arrangement of parts to be hereinafter more fully described, claimed and illustrated in the accompanying drawings, in which:

Figure 1 is a top plan view of a can equipped with the closure. Fig. 2 is a sectional view on line 2—2 of Fig. 1. Fig. 3 is a plan view of the closure, the locking plate removed. Fig. 4 is a side elevation. Fig. 5 is a sectional view on line 5—5 of Fig. 1. Fig. 6 is a sectional view on line 6—6 of Fig. 1.

Referring to the drawing the numeral 1 designates the can having the usual neck 2 which terminates in an outwardly flared rim 3, said rim having its upper edge provided with an annular flange 4, said flange being provided with paired notches 5, the purpose of which will appear later.

The cover 6 is provided with an annular flange 7 which is adapted to engage the flange 4 of the neck, and is provided with diametrically disposed lugs 8 which are adapted to engage in the depressions 9 formed in the flange 4, and when engaged

thus it is obvious that relative rotation of the cover and neck is prevented, but at the same time permitting the cover to be readily lifted from engagement with the neck.

A strip 10 is provided and has its ends provided with arcuate heads 11 which are provided with ears 12, said ears being riveted or otherwise secured to the cover 6 so that the plate will be in a plane with the flange 7, said strip being further provided with an opening 13 and in which is engaged a bolt 14. Pivotedly connected to the strip 11 by the bolt 14 is a locking plate 15, said plate having arcuate heads 16 which are provided with inwardly bent ears 17, said ears being adapted to pass through the notches 5 and upon partially rotating the plate 15, the ears will engage under the flange 4 of the neck, thus holding the cover firmly in place.

The locking plate 15 has formed therein a chamber 18, which terminates on one of the heads 16 in an angular chamber 19. Fixed in any suitable manner in the chamber 18 is a rod 20, said rod having an angular arm 21, which is engaged in the chamber 19 and has its end sharpened, as at 22. The arm 21 is resilient so that it will yieldably engage the surface of one of the heads 11 of the strip 10.

One of the heads 16 is provided with a sight opening 23 which is closed by the glass 24, whereby the card 25 having printed thereon the consignee's name can be readily observed, said card being pasted on the adjacent head 11 of the plate 10 so as to be in the path of movement of the sharpened end 22 of the arm 21 when the locking plate 15 is rotated. Thus it will be seen that should a person attempt to open the can the sharpened end 22 of the arm 21 will mutilate the card.

The cover is placed in the neck after which the ears 17 of the heads 16 are passed through the notches 5, after which the locking plate is turned clockwise so that the sharpened end 22 of the arm 21 will ride over the card 25, and at which time the locking plate and strip are in direct alinement. Now, to open the can it is necessary to rotate the locking plate 15 so as to bring the ears 17 in registry with the notches 5. Thus it will be seen that when the locking plate is turned anti-clockwise that the sharpened end 22 of the arm 21 will remove or mutilate the card 25, thus indicating that the can has been opened in transit.

What is claimed is:—

1. The combination with a can, of a cover therefor, a strip supported transversely of the cover, a locking plate pivotally connected to the strip and having a resilient arm associated therewith adapted to slidably engage the strip when the locking plate is rotated, as and for the purpose set forth.
2. The combination with a can having a neck, of a flange carried by the neck and having notches formed therein, a cover removably mounted in the neck and having a strip fixed transversely thereof, a locking plate pivotally connected to the strip and having heads formed upon its ends, ears car-

ried by the heads for passage through said notches, an arm associated with the locking plate and yieldably and slidably engaged with the strip, a card associated with the strip and adapted to be engaged by said arm 20 when moved in one direction to mutilate or remove the card, as and for the purpose set forth.

In testimony whereof, I affix my signature, in the presence of two witnesses.

ALVA L. BROWN.
